(57) **CLAIM**

The ornamental design for a dome light for a vehicle, as shown and described.

DESCRIPTION

FIG. 1 is a perspective view of a dome light for a vehicle showing our new design;

FIG. 2 is a bottom plan view thereof;

FIG. 3 is a side elevational view thereof, the opposite side elevational view being a mirror image thereof; and,

FIG. 4 is one end view thereof, the opposite being a mirror image thereof.

The back of the dome light is substantially unornamented.
